[54] **FLOOR COVERING COMPOSED OF RELEASEABLY
CONNECTED HOLLOW BODIES**
10 Claims, 11 Drawing Figs.

ABSTRACT: A floor covering has a series of adjacent elongated hollow bodies, each with a projection on each end face, interconnected by means of staggered inclined fish plates, each engaging with its end portions two adjoining projections while each projection engages an end portion of two adjoining fish plates.

**FLOOR COVERING COMPOSED OF RELEASEABLY
CONNECTED HOLLOW BODIES**

The invention relates to floor coverings for the rapid construction of roads, bridges, one-ways and landing paths, platforms and the like, composed of a series of closely adjacent and releasably interconnected four-cornered hollow bodies. The hollow bodies preferably are composed of steel, and have abutting outer surfaces for the transmission of load moments among adjoining hollow bodies, and these abutting outer surfaces are made in the fashion of slot and key. They are in articulate abutment, preferably in the form that each hollow body has one concave abutment surface and one convex abutment surface, the latter being made of a cylindrical tube, and the upper and lower covers of the hollow body are connected to the top and bottom respectively of the cylindrical tube, for instance by welding.

It is among the principal objects of the invention to provide a floor covering of the type referred to, the hollow bodies of which are simple to handle and may be quickly and reliably connected to each other.

Further objects and advantages of the invention will be set forth in part in the following specification and in part will be obvious therefrom without being specifically referred to, the same being realized and attained as pointed out in the claims hereof.

Generally, the instant invention achieves the foregoing aims providing elongated hollow bodies that have each a pin on each end face. A projection extends from each pin beyond the respective end face, and is recessed. Each two adjoining hollow bodies are interconnected by means of a connecting link or fish plate, and each projection is engaged by two fish plates. The fish plates are in overlapping relationship and inclined relative to the end surfaces. The outer of the two fish plates on each projection engages the recess of the projection. Each fish plate has two apertures that are spaced from each other for a distance comparable to the distance between the projections of two adjoining hollow bodies, and preferably the apertures are elongated in the longitudinal direction of the fish plate.

The placing of the covering is simple. First there is mounted onto the first hollow body on both end faces on each projection a fish plate the aperture of which rests on the recess of the projection. Thereafter, the free end of each fish plate is placed with its aperture onto the projection of the next adjoining hollow plate to engage that portion of the projection that is disposed between the root of the pin and the recess; and onto this last named projection a second fish plate is mounted outwardly with respect to the previously mounted fish plate and engages the recess of that last named projection, so that the last named fish plate will overlap the previously mounted fish plate and will retain it in its projection due to the engagement of the last named fish plate with the recess. During the connection to the next (third) hollow body, the same procedure is observed. The very last fish plate at the termination of the floor covering may be secured, for instance by a clamp strap. In order to exchange hollow plates, either because they may have been damaged or for any other reason, and to carry out the exchange quickly without need to disassemble the entire floor covering, the invention provides that at least some of the hollow bodies are interconnected by fish plates that are composed of separable parts and connected between the ends of the fish plates. Such a modified fish plate may, for instance include two elongated parts that overlap for a portion and be interconnected by screws; but may also be made more elaborately, for instance in the manner of a turn buckle.

In accordance with a preferred embodiment, one elongated surface of each hollow body is concave in accordance with a half cylinder and engages the half cylindrical convex elongated surface of the next adjoining hollow body. The concave surface forms a part of a half cylindrical tubular piece, while the convex elongated surface forms part of a cylindrical tube; and the root portion of the pin fits telescopingly into the cylindrical tube and is welded thereinto.

It is particularly suitable to provide that portion of the projection of the pin that extends between the recess and the root of such a large dimension that its height is somewhat larger than the width of the recess.

5 In muddy terrain, the instant floor covering has been found to be useful particularly in connection with a further improvement that provides that hollow bodies of similar construction are placed in a second layer below the layer of the floor covering, and at right angles to the longitudinal extension of the hollow bodies of the upper layer.

10 For the use of the floor covering in road building, it is advantageous to provide in a lower layer two rows of hollow bodies that correspond to road lanes, and if desired to provide in that lower layer a double row composed of two adjoining hollow bodies under each lane, serving as a sort of foundation. This provides for an excellent longitudinal rigidity.

15 The hollow bodies in accordance with the invention are particularly easy to handle, because they may easily be lifted with a crane, by attaching the loop of a rope around the two-end surface projections; and furthermore the hollow bodies may be supported on parallel bars which preferably have a shape that matches the recesses of the projections, and thus be suspended and transported.

20 25 In accordance with a further embodiment of the invention, the hollow bodies may be made of trapezoidal shape, and each body will have at least one vertical bore near its narrow end, and at least two such vertical bores near the other end, in both the upper and lower covers, to receive ground engaging pins.

30 In accordance with a further embodiment, corrugated sheet metal or friction generating synthetic material may be provided for the upper and lower covers, to prevent slipping of the floor covering on the ground.

35 The instant invention has the advantages that for the rapid construction of roads and the like that include curved portions, there is needed but a single main building element, namely the hollow body. With the trapezoidal hollow body, such curves may be produced by joining successive hollow bodies of the same lateral direction, that means that the 40 shorter side of one hollow body is placed next to the shorter side of the adjacent hollow body. For a floor covering of a straight road section, the same trapezoidal hollow bodies may be used, by placing the shorter end of one hollow body to the wider end of an adjoining hollow body, but yielding a straight horizontal surface. For attaching the floor covering to the ground, ground engaging pins are driven through the aforesaid bores of the hollow bodies into the ground. The aforesaid bores extend through the entire height of the hollow body, including the upper and lower covers thereof.

50 For a fuller understanding of the nature and objects of the invention, reference should be had to the following detailed description, taken in connection with the accompanying drawings, in which:

55 FIG. 1 is a fragmentary sectional view of a portion of a floor covering, in accordance with an embodiment of the invention, showing parts of two hollow bodies, projections thereof and overlapping fish plates interconnecting them;

FIG. 2 is a plan view of a fish plate of the type shown in FIG. 60 1;

FIG. 3 is a fragmentary sectional view similar to FIG. 1, but embodying a modified fish plate;

FIG. 4 is a fragmentary sectional view of a pin with projection and recess in accordance with an embodiment of the invention;

FIG. 5 is an elevational view of the pin shown in FIG. 4;

FIG. 6 is a plan view of a hollow body in accordance with a preferred embodiment;

FIG. 7 is a side elevational view thereof;

FIG. 8 is an end elevational view of the hollow body of FIGS. 6 and 7;

FIG. 9 is a fragmentary large scale plan view, showing a floor covering;

FIG. 10 is a large scale side elevational view of a fish plate; and

FIG. 11 is a large scale side elevational view of a clamp strap.

Referring particularly to FIGS. 1 and 2, a hollow body or hollow bodies 1 are provided that includes a cylindrical tube 2 welded into the hollow body 1. A pin 3 laterally is inserted into each tube 2, and the root of each pin 3 fits in telescoping fashion into the tube 2, and is connected thereto, for instance welded thereto. A cylindrical projection 4 extends from the root of the pin 3, and has a recess 5. Between the recess 5 and the root there extends a portion, the height of which is slightly larger than the width of the recess 5.

Fish plates or connecting links 6 are provided that interconnect adjoining projections 4. The connection is done in such a manner that the end portion 6a of the fish plate 6 that is outermost on the pin 3 (see the left-hand side of FIG. 1) overlaps a portion of the inner fish plate 6, and engages the recess 5.

Each fish plate preferably is provided with two elongated apertures, the direction of elongation of which coincides with the longitudinal direction of the fish plate 6. The fish plate 6 engages with its apertures 7 the projections 4 of the pins 3. At least some of the pins may be constructed in accordance with FIG. 3, namely be composed of two parts 6' and 6" respectively, that are interconnected by means of screws or bolts 8. These type fish plates may thus be taken apart intermediate their ends, and thereby facilitate the removal of any one hollow body 1.

In accordance with the construction shown in FIG. 7, the hollow bodies 1 are provided in a layer, namely an upper layer, and below that there is provided a lower layer 9' composed of similar hollow bodies but disposed at right angles to the hollow bodies 1 of the upper layer. As best shown in FIG. 7, the lower layer may provide a foundation for each lane, if the floor covering be a roadway, and each such support or foundation for each lane may be composed of two adjoining hollow plates (as shown on the left side of FIG. 7) or of three hollow bodies (as shown on the right-hand side of FIG. 7). While two and three hollow bodies are shown adjacent in the lower layer, this number may of course be varied in accordance with need, as will be obvious to the skilled artisan.

In accordance with a preferred embodiment, each hollow plate 1 may have a trapezoidal shape. As best shown in FIG. 8, each hollow body 1 has an upper plate 10 and a lower plate 11, that may be made of steel. One of the longitudinal sides 2' serves as "slot" for the slot and key connection, and includes a semicylindrical half tube that presents a concave outer surface, and the other longitudinal side is composed of a cylindrical tube 2 that serves as the "key" for the slot and key connection, and that presents an external convex surface; the convex longitudinal surface of one hollow body 1 matches the concave longitudinal surface of the next adjoining hollow body 1, and forms therewith an articulate connection, when attached thereto with the fish plates 6. The tube 2 and the semicylindrical half tube 2' are welded to the upper and lower covers 10 and 11, respectively.

Near the narrower end there is provided a vertical bore 12, and near the wide end of the hollow body 1, there are provided two vertical bores 13, which are similar to the bore 12. While only one bore 12 and two bores 13 are shown in FIG. 6, it will be understood that more than one bore 12 and more or fewer than two bores 13 may be provided instead. They serve to receive ground engaging pins (not shown).

On each end face the tube 2 carries a pin 3, and each pin 3 has a projection 4 of the aforesaid type. The projections 4 carry the fish plates 6 (see, for instance, FIG. 10); at least the last fish plate 6 is secured against accidental removal by means of a clamp strap 14 (See FIG. 11).

As shown in FIG. 9, a straight floor covering may be

produced by placing the hollow bodies 1 in such a manner that each narrow end of one hollow body is placed near the wide end of the next hollow body. To support the floor covering, there may be provided below the upper layer of the floor covering a lower layer, that, as schematically indicated in FIG. 9, may be composed of hollow bodies 9' of the same type as the hollow bodies of the upper layer.

In all the disclosed embodiments, the upper as well as the lower covers 10 and 11, respectively, may be provided either with a corrugated sheet or with a slip-preventing synthetic material.

I wish it to be understood that I do not desire to be limited to the exact details of construction shown and described, for obvious modifications will occur to a person skilled in the art.

15 I claim:

1. A floor comprising a series of adjacently positioned and releasably connected elongated hollow bodies, each hollow body including an upper cover and a lower cover, a semicylindrical longitudinal wall forming a concave outer lateral surface, a cylindrical tube connected to said upper and lower covers and forming a longitudinal wall defining a convex outer lateral surface opposite and matching in length and curvature said concave outer surface, whereby the concave outer lateral surface of one hollow body may engage the convex outer lateral surface of the next adjoining hollow body, a pin mounted on each end of said tube and including a projection extending outwardly beyond each end face of said tube, said projection having a recess, a series of overlapping connecting links inclined relative to said end faces, each connecting link interconnecting with its end portions the projections of two adjacent hollow bodies, each projection engaging one end portion each of two adjoining connecting links, the outer of said connecting links on each projection engaging with its end portion said recess.
- 20 2. A floor covering, as claimed in claim 1, the inner of said connecting links engaging with its end portion a projection near the root thereof.
- 25 3. A floor covering, as claimed in claim 1, said hollow bodies being of welded steel construction, each pin including a root fitting telescopingly into said tube and being welded thereto.
- 30 4. A floor covering, as claimed in claim 1, said connecting links being longitudinal, each end portion of each connecting link having an elongated aperture, the direction of elongation of the apertures coinciding with the longitudinal direction of the connecting link.
- 35 5. A floor covering, as claimed in claim 1, each connecting link including two parts releasably interconnected between the end portions.
- 40 6. A floor covering, as claimed in claim 1, each hollow body being of trapezoidal shape.
- 45 7. A floor covering, as claimed in claim 6, each hollow body having near its narrow end at least one bore for receiving a ground engaging pin, and having near its wide end at least two of said bores.
- 50 8. A floor covering, as claimed in claim 1, said upper and lower covers including corrugated sheet material.
- 55 9. A floor covering, as claimed in claim 1, said upper and lower covers including a friction promoting coat of synthetic material.
- 60 10. A floor covering, as claimed in claim 1, said series of hollow bodies defining an upper layer for a roadway, and a lower layer below said upper layer and comprising a plurality of said hollow bodies positioned at right angles to the hollow bodies of the upper layer and forming a lane foundation for the roadway.
